TURBOTRANSMISSION

Joseph R. Teagno, Detroit, Mich.

Application May 28, 1941, Serial No. 395,664

8 Claims. (Cl. 60—54)

This invention relates to turbotransmissions and more particularly to means for controlling the movement of the reaction member thereof.

Broadly the invention comprehends a turbotransmission including means responsive to the fluid force and operative to engage and disengage the reaction member from the fluid circuit to permit function of the unit as a torque converter or fluid coupling.

An object of the invention is to provide means for controlled movement of the reaction member into and out of the fluid circuit.

Another object of the invention is to provide a means for permitting movement of the reaction member linearly parallel to the axis into and out of the fluid circuit.

Another object of the invention is the provision of a turbotransmission including means responsive to fluid directional flow within the turbo for controlling the movement of the reaction member.

A further object is to provide a turbotransmission including fluid direction pilot vanes for advancing and retracting the reaction member into and out of the fluid flow.

A still further object is the provision of a turbotransmission including adjustable fluid direction pilot vanes for controlled movement of the reaction member.

And yet another object is the provision of a turbotransmission including a set of fluid direction pilot vanes adjustable to any desired torque multiplication to thereby advance or retract the reaction member as the torque demands.

Another object of the invention is to provide a turbotransmission including reaction vanes, adjustable fluid direction pilot vanes, and means carried by the pilot vanes for advancing and retracting the reaction vanes from the fluid flow.

Other objects and advantages of the invention will appear from the following description taken in connection with the drawing and in which—

Fig. 1 is a sectional view of a torque converter embodying the invention;

Fig. 2 is a diagram illustrating the relation of the pilot vanes and reaction member vanes to the first and second stages of the turbine showing the directional characteristics of fluid flow at the initial speed of the turbine; and

Fig. 3 is a diagram illustrating the relation of the pilot vanes and reaction member vanes to the first and second stages of the turbine showing the directional characteristics of fluid flow at increased speed.

Referring to the drawing for more specific de-

tails of the invention, 10 represents the crank case of an internal combustion engine, and 12 the crank shaft of the engine. The crank case has secured thereto a bell housing 14 having therein 16 a reservoir 16 provided with a filling opening 18 normally closed as by a plug 20.

The reservoir has an annular hollow flange 22 communicating directly with the reservoir, and the flange is provided with an inlet port 24 and a discharge port 26. A ring 28 mounted on one side of the flange, supports a fluid seal 30, and mounted on the other side of the flange is a pair of oppositely disposed rings 32 and 34. The ring 32 has internal splines 36, and the ring 34 supports a bearing 38 and a fluid seal 40, and the bearing 38 is in axial alignment with the crank shaft 12.

A torque converter, indicated generally at 42, includes a housing 44 having a hub 46 bolted or otherwise secured to the crank shaft 12, and an oppositely disposed hub 48 supporting a ring 50 embraced by the fluid seal 30. The housing 44 has thereon a ring gear 52 for connecting a starter, not shown, and a plurality of impeller blades 54 are suitably mounted on the inner wall of the housing 44.

A rotary pump 56 includes a housing 58 having an eccentric chamber 60, an inlet port 62, and a discharge port 64 communicating with the housing 44 of the converter, and a rotor 66 movable in the housing. The rotor 66 includes a hub secured to the crank shaft 12, and a concentric shaft 68 extended through a closure plate 70 on one side of the housing. The shaft 68 has secured thereto blades 72 fitted in the chamber 60. The rotor 66 is concentrically bored, and fitted in the bore is a bearing 74 in axial alignment with the crank shaft 12.

A center shaft 76 supported for rotation on the bearings 38 and 74 in axial alignment with the crank shaft 12, has splined thereto a clutch member 78, and journaled in the center shaft is a driven shaft 80 having thereon a clutch member 82 for cooperation with the clutch member 78. The center shaft 76 is splined to the housing 58 of the pump, and a turbine 84 rotatable in the housing 44 includes a web 86 supported on and secured to the pump housing 58 for rotation therewith, and the web supports a two-stage turbine 88 and 90.

As shown, the first stage of the turbine consists of a plurality of vanes 92, suitably secured to an outer shroud 94 and to an inner shroud 96. The inner shroud 96 is fixedly secured to an inner shroud section 98 adjacent the impeller blades 54 and the shroud section 98 is fixedly secured to

another inner shroud section 100 secured to a plurality of vanes 102 mounted on the web 86. The vanes 102 constitute the second stage of the turbine.

A sleeve 104 slipped over the center shaft 76 and fixedly secured to the ring 32 by the splines 36, is supported in spaced relation to the center shaft and provides in conjunction therewith an annular passage 106 for delivery of fluid from the discharge port 26 of the reservoir to the intake port 62 of the pump 56. Fluid is delivered by the pump into the housing 44, and returns from the housing to the reservoir through ring 50 on the hub 48 of the housing 44 and the inlet port 24 of the reservoir.

The sleeve 104 has a splined portion 108 and a circumferential groove 110 and fitted for axial movement in the splined portion is a reaction member 112 retained in one direction of movement by a ring 114 fixedly secured to the sleeve 104. Fitted for free rotation in the circumferential groove 110 is a fluid direction pilot member 116.

The reaction member 112 includes a heavy sleeve 118 supporting a web 120 movable in the housing 44. A plurality of vanes 122 are mounted on the web and support a shroud 124. The sleeve 118 has an inner spline 126 corresponding to the spline 108 on the sleeve 104 and also an external thread 128.

The fluid direction pilot member 116 includes a rimmed section 130 having internal threads 132 for cooperation with the threads 128 of the reaction member and a web 134 supported by the rimmed section has thereon a plurality of adjustable pilot vanes 136. A flange 138 on the rimmed section 130 corresponds to the circumferential groove 110 of the sleeve 104. The web 134 has a plurality of openings 140 therethrough to provide a free passage of fluid from the housing to the inlet port 24 of the reservoir.

The pilot vanes 136 mounted on the web 134 and pivotal on pins 142 have screws 144 passing through arcuate slots 146 in the web 134 so that the vanes may be secured in any predetermined position. This position is determined by the point in the torque multiplication curve where it is desired to move the guide vanes from the fluid circuit and to again return them. The fluid action upon which the pilot vanes depend to function is derived automatically from the torque demand placed upon the turbine. This demand causes the absolute angle of discharge of fluid from the first stage of the turbine to shift so as to act alternately upon the desired surface of the vanes 136 to thereby advance or retract the reaction member 112.

In a normal operation assuming that the unit is filled to its normal capacity with suitable fluid, transmission of force from the power plant or internal combustion engine through the crank shaft 12 results in driving the pump and the impeller. The pump delivers fluid to the impeller at a rate proportionate to the rate of speed of rotation of the crank shaft. The impeller energizes the fluid, and the energy of the fluid is received on the vanes 92 constituting the first stage of the turbine, the vanes 136 of the fluid pilot member, the vanes 122 of the reaction member, and the vanes 102 of the second stage of the turbine causing rotation of the turbine.

This rotation of the turbine results in driving the center shaft 76 and the driven shaft 80 clutched thereto. Upon rotation of the center shaft the rotary pump 56 is driven and, accord-

ingly, the pump delivers a smaller volume of fluid to the impeller because at this period the rotor of the pump and the housing of the pump are rotating in the same direction.

- 5 As the speed of rotation of the impeller and the turbine increase, the energy of the fluid increases proportionately, and this increased energy of the fluid acting on the vanes 92 of the turbine causes increase in speed of the turbine.
- 10 As this increased speed of the turbine approaches that of the impeller, the angle of the fluid leaving the first stage of the turbine shifts from impinging on the faces of the vanes 136 to impinge on the backs of the vanes, causing the rotation of 15 the fluid direction pilot means 116 in the groove 110 to thereby spiral on the threaded sleeve of the reaction member 112 so as to move the reaction member out of the fluid circuit in a plane parallel to the axis of rotation. With the increased energization of the fluid by the impeller 20 the reaction member is moved from the circuit by the action of the pilot means until the reaction member has moved to its fully retracted position and thereupon locks the member against the resistance of the fluid force impinging on the 25 vanes of the member. Hereafter the turbotransmission functions as a fluid coupling.

Upon decrease in speed of rotation of the impeller and the turbine, the energy of the fluid 30 decreases proportionately and the volume of fluid delivered by the pump increases proportionately. The fluid discharged from the first stage of the turbine now impinges on the faces of the vanes 136 of the pilot member causing the reaction member 112 to move into the fluid circuit upon the consequent rotation and spiralling of the threads of the fluid pilot member 116. The inward movement of the reaction member into the fluid circuit is limited by the retaining ring 114.

40 It is obvious from the foregoing that the pump 56 delivers fluid to the impeller at a rate proportionate to the relative speed of the impeller and the turbine, and that the maximum volume of fluid is delivered to the impeller when the turbine is static and the impeller is rotating at stalling speed, and, correspondingly, the minimum volume of fluid is delivered by the pump to the impeller when the unit is operating at its maximum efficiency, that is, when the least degree of slip exists between the impeller and turbine.

45 While this invention has been described in connection with certain specific embodiments, the principle involved is susceptible of numerous other applications that will readily occur to persons skilled in the art. The invention is, therefore, to be limited only as indicated by the scope of the appended claims.

50 Having thus described the various features of the invention, what I claim as new and desire to secure by Letters Patent is:

1. In a fluid transmission, an impeller, a turbine providing in conjunction therewith a fluid circuit, reaction vanes lineally movable into and out of the fluid circuit, and independent pilot vanes coupled to the reaction vanes and rotatable in the fluid circuit actuated by fluid directional flow in the circuit for controlling the movement of the reaction vanes.
- 55 2. In a fluid transmission, a primary means for energizing the fluid, a secondary means for receiving energy from the fluid, reaction vanes for deviating the fluid movable into and out of the fluid flow, rotative means in the fluid flow, and means coupling the reaction vanes and

rotative means for controlling movement of the reaction vanes, said means having solely rotative movement.

3. A fluid transmission comprising a primary fluid energizing means and a secondary means for receiving energy from the fluid providing in conjunction with one another a fluid circuit, a stationary member, a reaction member supported on the stationary member and movable axially thereon into and out of the fluid circuit, and a pilot member in the circuit rotatable in a groove on the stationary member and cooperating with the reaction member for controlling the movement of the reaction member.

4. A fluid transmission comprising a primary means for energizing fluid and secondary means for receiving energy from the fluid providing in conjunction with one another a fluid circuit, reaction vanes lineally movable into and out of the fluid circuit, and pilot vanes in the circuit having threaded engagement with the reaction member for controlling the movement thereof said pilot vanes being rotatable in one direction by means of fluid impinging on their backs and rotatable in the other direction by means of fluid impinging on their faces, the rotation thereof being limited dependent on the axial movement of the reaction vanes.

5. In a turbine power transmission, a driving shaft, a driven shaft, a primary wheel mounted on the driving shaft, a secondary wheel mounted on the driven shaft, a stationary member, said primary and secondary wheel providing in conjunction with one another a fluid circuit, a reaction member mounted on the stationary member and movable axially thereon into and out of the fluid circuit, a pilot member supported on the stationary member and rotatable thereon, and means between the pilot member and reaction member for controlling the movement of the reaction member, said pilot member being cooperation with the fluid circuit during all phases of operation of the turbine.

6. A fluid power transmitter comprising a

primary means for energizing the fluid and a secondary means for receiving energy from the fluid providing in conjunction therewith a fluid circuit, a stationary member having a straight spline and a circumferential groove, a reaction member cooperating with and axially movable into and out of the fluid circuit on the spline of the stationary member, and a pilot member in the circuit actuated by fluid flow thereon effecting rotation thereof having a part rotatable in the circumferential groove and a part engaging the reaction member for controlling the movement thereof.

7. A fluid transmission comprising an impeller having fixed blades, a turbine having fixed vanes and providing in conjunction with the impeller a fluid circuit, a reaction member having vanes movable into and out of the fluid circuit, a pilot member having vanes rotatable in the circuit, and means for coupling the reaction member to the pilot member to provide for movement of the reaction vanes axially lineally into and out of the circuit upon rotation of the pilot member due to directional fluid flow in the circuit.

8. In a fluid transmission, an impeller, a turbine providing in conjunction therewith a fluid circuit, a reaction member axially lineally movable into and out of the fluid circuit, a pilot member having vanes in the circuit responsive to directional fluid flow therein providing for rotation thereof, said pilot member rotatable in a reverse direction to the turbine and impeller and relative to the reaction member during one phase of operation of the transmission and rotatable in the same direction as the turbine and impeller and relative to the reaction member during another phase of operation of the device, and a threaded connection between the pilot member and reaction member whereby the reaction member moves axially lineally when the pilot member rotates.

JOSEPH R. TEAGNO.
